UNITED STATES PATENT OFFICE

2,523,824

BURIAL VAULT COVER

Wilbert W. Haase, Forest Park, Ill., assignor to
 Wilbert Manufacturers Association, Forest
 Park, Ill., a corporation of Illinois

Application September 15, 1945, Serial No. 616,628

1 Claim. (Cl. 72—7)

1

This invention relates to a burial vault cover and, more particularly, to a cover for a concrete burial vault.

Heretofore in the art it has been common practice for manufacturers of concrete burial vault covers to unload the same at some convenient and unobtrusive point in a cemetery prior to the interment. After interment the burial vault cover is moved by means of a wheel-bearing grave vault cover carrier to a point adjacent the grave opening in which the body or base of the vault with the casket therein are arranged.

In order to move the burial vault cover into the grave opening a portable trackway is provided and one typical form of such a trackway is shown in my United States Patent No. 2,112,286 granted March 29, 1938, on "Burial Apparatus." Such a trackway is provided with parallel guide rails each having a portion extending to one side of the grave opening. These parallel guide rails are adapted to support a grave vault cover carrier provided with flanged guide wheels and such a burial vault cover carrier is shown in my aforesaid patent. The burial vault cover is laid upon this carrier and moved thereon into a position over the grave opening into which it is lowered by any suitable burial vault lowering or winch device.

While burial vault cover carriers of the character shown in my aforesaid patent are, in general, quite satisfactory they are somewhat expensive to manufacture and hence add materially to the funeral director's investment.

Accordingly, an object of the present invention is to provide a novel concrete burial vault cover which in use eliminates the need for the use of the burial vault cover carriers heretofore used for moving burial vault covers from a point adjacent a grave opening into a position above the grave opening.

Another object of the invention is to provide a novel concrete burial vault cover having formed integrally therein shaft bearing openings, each adapted to have removably inserted therein a shaft or trunnion bearing a flanged anti-friction roller or guide wheel to the end that the new concrete burial vault cover may be moved upon said flanged guide rollers across a trackway from a point adjacent a grave opening to a point above the grave opening and the burial vault cover then raised slightly and the detachable guide roller shafts, with the flanged guide rollers thereon, then removed from their bearing openings or sockets in the body of the burial vault cover.

Other and further objects of the present in-

2

vention will be apparent from the following description and claim and are illustrated in the accompanying drawing which, by way of illustration, shows a preferred embodiment of the invention and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claim.

In the drawings,

15 Fig. 1 is a top plan view illustrating the new concrete burial vault cover and showing the same in full lines disposed in a position adjacent a grave opening and ready to be moved into a position above the grave opening and in which latter position it is shown in dotted lines in Fig. 1;

20 Fig. 2 is an edge elevational view on line 2—2 in Fig. 1; and

25 Fig. 3 is an enlarged fragmentary detail view of the new concrete burial vault cover on line 3—3 in Fig. 2, showing one of the shaft or bearing sockets formed therein and showing one of the shafts or trunnions removably mounted in said bearing opening or socket.

30 A typical embodiment of the new concrete burial vault cover is illustrated in Fig. 1 of the drawing, wherein it is generally indicated at 10, and comprises a substantially rectangular body 11 suitably sized, shaped, and formed to fit upon the body of a concrete burial vault (not shown) of a corresponding size and shape, and which may be of the general construction shown in my United States Patent No. 1,839,149 granted December 29, 1931, on a "Burial Vault."

35 The body 11 of the new concrete burial vault cover 10 has four substantially similar sockets or bearing openings 13 formed therein, one at each corner thereof, and each of these bearing openings or sockets 13 is adapted to have a guide roller shaft or trunnion 12 removably journaled therein.

40 45 The sockets or bearing openings 13 may be formed in any suitable manner in the concrete of which the grave vault cover 10 is composed as by having the concrete poured around a suitable mold during the operation of forming or molding the new concrete vault cover.

45 50 Each of the trunnions or shafts 14 has a reduced end portion 14, providing a shoulder 15, and a flanged guide roller 16 is rotatably mounted on the reduced end portion 14 of each of the 55 trunnions or shafts 12 and is held thereon in any

suitable manner as by means of a retaining nut 17 threaded onto a threaded outer end of each shaft 12, as shown in the drawing.

The long axes of the bearing sockets or shaft openings 13 and the trunnions or shafts 12 removably mounted therein extend parallel to each other and to the long axis of the body 11 of the burial vault cover 10.

In the use of the new concrete burial vault cover shown in the drawing a guide rail 18 is arranged at each side of the grave opening 20, these guide rails 18 being mounted on supporting feet or pedestals 19, which may be a part of a burial vault lowering device, one of these supporting pedestals 19 being arranged at each corner of the grave opening 20, as shown in Fig. 1. Each of the guide rails 18 is supported by two of the supporting feet or pedestals 19.

A burial apparatus of the character which may be employed in manipulating the body of the grave vault and the new grave vault cover is shown in my United States Patent No. 2,112,286 granted March 29, 1938, on "Burial Apparatus" and embodies a pair of winch shafts (not herein shown) but one of which extends between each pair of adjacent supporting feet or pedestals 19. Each of such winch shafts has a pair of flexible members windable thereon and by means of which the body or base of the burial vault and its cover may be lowered into a grave opening.

In the use of the new burial vault cover, the same may be transported to the cemetery and the shafts or trunnions 12 slipped into their bearing sockets or shaft openings whereupon the grave vault cover 10 with the guide rollers 16 thus mounted thereon may be lowered onto the guide rails 18 at one side of the grave opening. After interment the burial vault cover 10 may then be rolled along the guide rails 18 into a position above the grave opening 20 and during this operation the flanged guide rollers 16 rotate upon the shafts 12 and are guided along the guide rails 18.

Accordingly, the body of the burial vault (not shown) has been lowered into the grave opening 20, and the casket lowered thereinto, the vault cover 10 may then be raised slightly by means of the vault lowering device, (not shown) so as to raise the flanged guide wheels or rollers 16 above the guide rails 18, and when thus raised the flanged guide wheels or rollers 16 and attached shafts or trunnions 12 may be detached from the body of the vault cover 10 by slipping the trunnions or shafts 12 out of their sockets or shafts openings 13. The lowering of the burial vault cover 10 may then be completed by means of a vault lowering device such as that to which I have referred above.

In order to prevent the two lead guide rollers 16 from running off the guide rails 18 during the operation of moving the burial vault cover 10 into position above the grave opening 20, a notch

or cut-out 21 may be provided in each of the guide rails 18 adjacent one end thereof (Fig. 1).

Hence it will be seen that the new grave vault cover having the flanged guide rollers 12 detachably mounted thereon dispenses with the need for a separate vault cover carrier device for transporting the vault cover over the guide rails 18 from a point adjacent the grave opening to a point above the grave opening and thus effects an economy in the investment required of the funeral director while, at the same time, simplifying the handling of the vault cover by reducing the amount of apparatus required to move the vault cover from a point adjacent the grave opening into a position above the grave opening.

It will thus be seen from the foregoing description, considered in conjunction with the accompanying drawing, that the present invention provides a novel concrete burial vault cover having the desirable advantages and characteristics, and accomplishing its intended objects, including those hereinbefore pointed out and others which are inherent in the invention.

I claim:

The combination with a trackway including spaced rails, each including a wheel restraining surface confining lateral movement of a wheel relative thereto and each rail extending transversely above and laterally of a grave opening, of a burial vault cover provided with spaced pairs of stub axle receiving sockets extending inwardly from the opposite end edges thereof, and a plurality of wheel assemblies each including a stub axle and a wheel operably supported thereon with the stub axles solely loosely engageable in the sockets, the wheels being engageable with the trackway to support the cover and each wheel having a surface engageable with the said restraining surface of the rails whereby the engagement between said surfaces constitutes means for retaining the axles temporarily in place in the sockets when the cover is moved from a position laterally of to a position over the grave opening or vice versa.
